UNITED STATES PATENT OFFICE

RUSSELL L. KLOTZ, OF LITTLE FALLS, NEW JERSEY

CHAIR

Application filed September 26, 1928. Serial No. 308,351.

This invention has for its object the provision of a chair which will support a person in a reclining position and which may be automatically set to support the user at a desired angle. The invention also has for its object the provision of a novel structure whereby the chair will be strong and durable and the backward motion of the back will be limited. Another object of the invention is to provide a construction and arrangement of parts which will permit the chair to be folded into small space when it is to be moved from place to place. Other objects will appear incidentally in the course of the following description, and the invention resides in certain novel features which will be particularly pointed out in the appended claims.

In the accompanying drawings:

Figure 1 is a side elevation of a chair constructed in accordance with the present invention;

Fig. 2 is a side elevation showing the chair collapsed or folded;

Fig. 3 is a front elevation, partly broken away, and

Fig. 4 is a detail perspective view of one arm of the chair with parts immediately adjacent the same.

In carrying out the invention, there are provided side arms each consisting of two bars 1 and 2 firmly secured together and each having a pendent portion 3 at its front end, the pendent portion of the inner bar 1 being wider longitudinally of the arm than the pendent portion of the bar 2 whereby a recess will be formed in which the upper end of the front leg 4 may be pivoted. At the rear end of the side arm, the bars 1 and 2 are also formed with depending portions 5 and a cross bar 6 is secured at its ends to the rear edges of said depending portions and extends across the back of the chair so as to impart rigidity to the supporting frame and also limit the rearward movement of the back, as will presently appear. To the outer side of the bar 2 at the rear end thereof is secured a spacer block 7 and to the outer side of said spacer at the rear end of the same is secured a stop block 8, the rear leg 9 being pivoted at its upper end to the spacer 7 immediately in

front of the stop 8 so that rearward movement of the leg will be prevented, and it may be noted that the depending front portion 3 of the bar 2 serves as a stop to prevent forward movement of the front leg. The pivots 10 and 11 for the front and rear legs are cylindrical studs or tenons formed at the ends of cross rods, one of which is indicated at 12, which extends entirely across the frame and have the shoulders formed by producing the tenons arranged to abut the inner sides of frame members and thereby prevent relative inward movement of said members so that the desired rigidity will be attained. The lower ends of the front legs are connected by a cross bar 12' secured to the same and the rear legs are connected in a similar manner by a cross bar 13, as will be understood. A brace 14 is pivoted at its front end to the outer side of the front leg adjacent the lower end of the same and at its rear end is engaged over a stud 15 on the inner side of the rear leg, as will be understood upon reference to Fig. 1, whereby relative spreading of the front and rear legs will be prevented and the supporting structure consisting of the side arms and the legs will be held against collapse while the chair is in use.

Through the outer ends of the trunnions or tenons 10 and 11 are inserted keys 16 which are tapered or wedge-shaped so that they may bind against the legs within the slots provided therefor and thereby frictionally resist turning movement of the legs and the other parts while they will also maintain the parts against outward separation.

Pivots mounted upon the front rod 12 are hangers 17 to the lower ends of which are secured by hinges 18 a foot rest 19 extending across the front of the chair and of any approved detail construction. To the forward corners of the foot rest are pivoted straps 20 which extend upwardly and rearwardly therefrom and are provided in their upper end portions with longitudinal series of openings 21 which are adapted to be selectively engaged over studs 22 on the outer sides of the hangers 17 whereby the foot rest may be adjusted to the needs of individual users. The back of the chair consists of two long

side bars 23 which are pivotally engaged over the rear rod or bar 12 and extend upwardly and downwardly therefrom, the upper ends of these side bars 23 being connected by a rod or round 24 whereby separation of the bars will be avoided. To the lower extremities of the side bars 23 are pivoted braces 25, which have their forward ends pivoted to a round 26 secured in and extending between the hangers 17 of the foot rest, the round 27 constituting the pivotal connection between the lower ends of the side bars 23 and the braces 25 which are so disposed that the several pivotal points 10, 11, 26 and 27 define the corners of a parallelogram, this arrangement permitting the chair to automatically assume the position desired by the user without liability of the chair to collapse. The seat or support for the user consists of a strip of fabric 28, preferably stout canvas, which is secured at its upper end to the round 24 and passes downwardly therefrom and then forwardly to pass over the upper front bar or rod 12 and then downwardly to be secured to the round 26, as will be understood upon reference to Fig. 1.

When the chair is in use, the sitter by merely leaning back to such angle as may be found most comfortable will automatically cause the hanger 17 and the side bars 23 of the back to swing about their respective pivot points 10 and 11 so as to support the sitter in the desired position, the hangers and the side bars being always in parallelism. Excessive backward movement of the side bars 23 is prevented by reason of their impact upon the stop bar 6 and the liability of the chair to tip over backwardly is thereby reduced to a nullity.

If it be desired to store the chair, the stop bar 6 is removed. The braces 20 are then disengaged from the studs 22 and moved into position substantially parallel with the hangers 17 or along the front edges of said hangers, this movement causing the foot rest to swing into position against the hangers, as shown in Fig. 2. The foot rest and the braces may then be tied to the hangers by any convenient means. The back of the device is then swung about its pivot 11 so that the upper end of the back swings forwardly and the lower end swings rearwardly, the foot rest and hangers following the movement which may be continued until the back comes into contact with the front bar 12 and practically rests upon the hangers. The braces 14 may then be released from the studs 15 and swung up alongside the respective front legs and the front legs then swung upwardly and rearwardly to positions alongside of the folded back, the folding operation being completed by swinging the rear legs forwardly and upwardly, as will be understood upon reference to Fig. 2. A cord or

other fastening means may then be tied around the folded structure so that the parts will be maintained in the collapsed condition.

From the foregoing description, taken in connection with the accompanying drawings, it will be seen that I have provided an exceedingly simple, strong and durable chair which may be used without fear of collapse and which will permit the user to assume such position as may be found most desirable.

Having thus described the invention, I claim:

1. A chair comprising side arms each having pendent portions at its front and rear ends, a bar rigidly connecting the rear ends of the side arms, legs pivoted to the depending portions of the side arms, stops on said depending portions holding the front legs against forward movement and the rear legs against rearward movement, connections between the lower ends of the legs, and a seat structure pivotally mounted between the side arms.

2. A chair comprising side arms each having depending portions at its front and rear ends, said depending portions having recesses at the outer sides of the arms, front and rear legs pivoted at their upper ends in the respective recesses, the front walls of the front recesses preventing forward movement of the front legs and the rear walls of the rear recesses preventing rear movement of the rear legs, connections between the lower ends of the legs, and a seat structure pivotally supported by and between the side arms.

In testimony whereof I affix my signature.
